UNITED STATES PATENT OFFICE.

JOSEPH W. LEWIS, OF PHILADELPHIA, PENNSYLVANIA, ASSIGNOR TO THE ATLANTIC REFINING COMPANY, OF PHILADELPHIA, PENNSYLVANIA, A CORPORATION OF PENNSYLVANIA.

METHOD OF AND APPARATUS FOR TREATMENT OF PETROLEUM.

1,364,443

Specification of Letters Patent.

Patented Jan. 4, 1921.

Application filed April 19, 1917. Serial No. 163,171.

To all whom it may concern:

Be it known that I, JOSEPH W. LEWIS, a citizen of the United States, residing in the city of Philadelphia, county of Philadelphia, and State of Pennsylvania, have invented certain new and useful Improvements in Methods of and Apparatus for Treatment of Petroleum, of which the following is a specification.

10 My invention relates to a method of and apparatus for treating crude petroleum, petroleum distillate or petroleum residuum, more particularly for the production of light hydrocarbons such as naphthas or 15 gasolines and burning or kerosene oil.

My invention resides in a method for the treatment of crude petroleum, petroleum distillate or petroleum residuum, as gas oil or fuel oil, or oils lighter or heavier than 20 gas oil or fuel oil, by subjecting the same to high temperature while maintaining thereon pressure which will more or less completely prevent fractional distillation of the oil treated, the applied heat effecting a 25 destructive distillation or dissociation or cracking of the heavier oils into naphthas or gasolines and burning oil of lower boiling points, and in general oils lighter in specific gravity, these resulting products comprising 30 both saturated hydrocarbons, so-called paraffins, or those which do not readily react with cold sulfuric acid of specific gravity 1.85 and which do not react with or absorb bromin or iodin, and unsaturated hydrocarbons, those which have unsatisfied bonds 35 and which readily react with the aforementioned acid and react with or absorb bromin or iodin, the entire change being effected during application of heat under the aforementioned pressure. The light hydrocarbon products readily distil off notwithstanding the pressure thereon, and the vapors of these products, together with some small amount of vapors of the heavier products, are preferably subjected to a preliminary cooling, as 40 in an air cooled condenser, whereby the vapors of the heavier oils are condensed and returned to the treating apparatus, while the vapors of the lighter products sought remain as such and pass beyond the preliminary cooling stage, whereupon their pressure is reduced, as by passing them through a reducing valve, to some lower pressure, preferably above atmospheric, and while under

such reduced pressure are subjected to the 55 principal cooling operation and condensed into liquid form, and while in liquid form are released to substantially atmospheric pressure and delivered to storage.

When employing a plurality or battery of 60 pressure stills each provided with a reducing valve for reducing the pressure of the resultant vapors from still pressure to some lower pressure, each still operates and is compelled to operate as an individual independently of all the others of the battery. In consequence the operation of each still is controllable independently of the others, with the result that its rate of firing, pressure and rate of production of distillate 70 are controllable independently of the other stills, with the further result that the yield and character of a desired product or products are controllable, with the result that the yield of the desired product or products 75 of the whole battery of stills may be made greater with greater uniformity of the desired product or products than the case where the stills of a battery are in communication with each other during operation. 80

While the vapors of the lighter products may be reduced in pressure to substantially atmospheric immediately after the preliminary cooling referred to, it is preferred to maintain them under suitable pressure during condensation to liquid form, for the purpose of reducing or minimizing the amount of light vapors held in the permanent gas which is a further product of the destructive distillation; and it will therefore be understood that the amount of the pressure maintained upon the vapors after passage through the reducing valve and before release to substantially atmospheric pressure is independent of the still pressure and produces no chemical effect upon or change in the light hydrocarbon products and serves to strip the gas of light oil vapors. By so operating upon the vapors they retain a greater proportion of the light vapors which otherwise would pass off in or with the gas. 95

The light hydrocarbons above referred to constitute a crude distillate which is then preferably treated as hereinafter described; and the residuum is preferably treated or 105 disposed of as hereinafter described.

My invention resides also in apparatus for treatment of petroleum or petroleum distil-

late or petroleum residuum for carrying out a method of the character above described or for any other suitable purpose.

For an illustration of one of the forms my apparatus may take and for one of the modes of carrying out my process, reference may be had to the accompanying drawings, in which:

Figure 1 is a side elevational view, partly in section, of pressure still apparatus and some of its adjuncts.

Fig. 1^a is a fragmentary plan showing connections from still to drum.

Fig. 2 is a fragmentary sectional view showing a part of the pressure still structure.

Fig. 3 is a fragmentary view, on enlarged scale, of the air cooled condenser, reducing valve and associated parts.

Fig. 4 is a fragmentary side elevational view, on enlarged scale, of part of the air cooled condenser and connections with the still.

Fig. 5 is a vertical sectional view, some parts in elevation, of a pressure reducing valve.

Fig. 6 is a diagrammatic view illustrating a battery of stills and adjuncts and a system of piping utilizable in carrying out my process.

Fig. 7 is a chart illustrative of a mode of treating pressure still products.

Referring to Fig. 1, S is a vertical still of boiler plate, provided with the man holes 1, 1 near its bottom and top. The oil to be treated is pumped into the still through the pipe 2 until it reaches the top of the pipe 3 within the still, which serves to indicate when the proper level has been reached by overflow through the pipe 3 and its control valve 4, appearance of oil at the outer and lower orifice of the pipe 3 indicating that the proper level is reached, whereupon the valve 4 is closed. Within the brickwork structure 5 are disposed the upper and lower cylindrical drums D and D¹, each connected at its one end by pipes 6 and 7, see Fig. 1^a, with the interior of the still S, the pipes 6 and 7 of each pair connecting to opposite sides of the still.

The drums D, D¹ are connected by the numerous substantially vertical metal tubes 8, as indicated in Figs. 1 and 2.

The chamber containing the drums and their connecting tubes communicates through the opening 9 with the firebox or chamber 10 in which is disposed the grate 11 on to which fuel is delivered from the chute 12 through the hopper or stoker 13, the ashes falling into the pit 14 and delivered therefrom to ash-removing cars 15. In the chamber containing the drums D, D¹ and the tubes 8 are the baffles 16, Fig. 2, with the result that the hot gases pass from the firebox or chamber 10 through the opening 9,

and between and around the upper parts of the tubes 8 and the drum D and pass downwardly in contact with the lower parts of the tubes 8 and the drum D¹ and hence into the flue passages 17, 17, Fig. 2, which communicate with a stack or chimney, not shown, which may be common to several stills. Communicating with the interior of the chamber containing the drums and tubes is a stack 18 having the closing cover 19, which latter may be moved to open position to allow escape of hot gases from the chamber, either in a measure to control the temperature to which the tubes 8 and drums D, D¹ are subjected, or rapidly to cool the chamber at the end of a run. At the upper end of the still S is the vapor outlet pipe 20, Figs. 1 and 4, communicating through valve 21 with the sweat-out line or pipe 22, and with the pipe 23 leading to the safety valve 24 whose discharge side communicates with the vertically extending pipe 25. The main vapor line 20 communicates also through the valve 26 with the upwardly and then downwardly extending vapor line or pipe 27 which communicates with the initial manifold or header 28 communicating with the three transversely extending initial header pipes 29 with which communicate the numerous small vertically extending pipes 30 connected in various groups through the top connecting pipes 31 with the numerous small downwardly extending pipes 32 communicating with the transverse terminal header pipes 33 which all communicate with the terminal header or manifold 34. The numerous pipes 30 and 32, and associated connections, are housed within the structure 35 open at its bottom and having at its top an open-work cover 36 of wire mesh or the like.

These pipes 30, 32 and their connections constitute means for preliminarily cooling the vapors rising from the still S and constitute the preliminary air cooled condenser, the cooling air entering at the bottom of the housing 35 and passing upwardly between the tubes 30, 32 and out through the open cover 36.

From transverse header pipes 29 and 33 extend downwardly the several pipes 37, Figs. 1 and 3, which communicate at their lower end with a pipe 38 from which is connected the riser pipe 39 controlled by valve 40 and communicating with the interior of the still S at its top, this piping structure constituting a runback whereby there are returned into the still S those heavy oils whose vapors have been condensed in the air condenser and which have been only partially, if at all, subjected to the desired treatment.

While it is preferred to resort to preliminary partial cooling of the vapors from the still, as by recourse to an air condenser or

its equivalent, my invention is not limited thereto and contemplates its omission.

Referring now more particularly to Fig. 3, there is connected with the header 34 of the air condenser a pipe 41, to which is connected the tell-tale pipe 42 controlled by valve 43, communicating through the valve 44 and the pipe 45 with the intake of the reducing valve 46 whose outlet communicates through the pipe 47 and the valve 48 with the vapor line or pipe 49. The pipes 41 and 49 are also connected through the normally closed by-pass valve 50.

The pressure-reducing means may be of any suitable type, a Watson reducing valve having been found satisfactory in operation.

In Fig. 5 is illustrated such a reducing valve in which the movable valve member 51 is attached to a stem 52 normally forced upwardly by the arm 53 pivoted at 54 and thrust upwardly by the spring 55. On the upper end of the stem 52 in the chamber 56 is the diaphragm 57 whose upper side is subjected to any suitable medium under pressure, as for example, compressed air delivered through the pipe 58 controlled by valve 59 and having the throttled outlet 60 to the space above the diaphragm 57. Communicating with the space above the diaphragm 57 is the tube 61 in which is disposed the vertically movable plug valve 62 whose upper end engages the stem 63 connected to the diaphragm 64 whose downward movement is opposed by the spring 65. With the space above the diaphragm 64 connects the pipe 66, controlled by a valve 67 and communicating through the valve 68, Fig. 3, with the pipe 41, a pressure gage 69, Fig. 3, being connected with the pipe 66 and showing the pressure upon the air condenser and still.

The air pressure exerts an upward force upon the plug valves 62 in opposition to the downward thrust upon the stem 63 occasioned by the still pressure upon the upper side of the diaphragm 64.

When the still pressure falls below a predetermined value, the spring 65 raises the stem 63, and the air pressure in the space above the diaphragm 57 is to some extent released, the escaping air passing out through the pipe 70. This reduces the pressure on the upper side of the diaphragm 57, allowing the spring 55 to move the valve stem 52 upwardly to move the valve member 51 toward its seat and therefore throttle the passage between the pipes 45 and 47, and so allowing less vapor to escape from the air condenser to the pipe 47; and due to this throttling action of the valve 51, upon subsequent rise in pressure in the still the diaphragm 64 will have greater pressure exerted on its upper side with a tendency to move the stem 63 and valve 62 downwardly and throttle the air escape through the

outlet 70 and thereby increase the pressure on the upper side of the diaphragm 57, with resultant downward movement of the stem 52 and the attached valve 51, thereby moving the latter farther from its seat and allowing freer passage of vapors from pipe 45 to pipe 47. In this way the reducing valve operates continuously to allow the vapors at still pressure to escape and assume in the pipe 47 and parts connected therewith a pressure lower than that in the still or air condenser, and in fact in the pipe 47 and connections any suitable pressure may be maintained, either at or preferably above atmospheric.

The vapors released through the reducing valve, through pipe 47, and valve 48, pipe 49, pass to a condenser coil or worm 71, Fig. 6, disposed in a box 72 through or in which cooling water or other cooling medium is circulated or maintained.

And the sweat-out pipe of line 22 connects with a small condensing worm or coil 73 similarly cooled by water or other suitable medium.

Referring to Fig. 6, three of a battery of stills and associated parts are shown.

Each condensing worm 73 in the sweat-out line connects by pipe 74 with the look box 75 which in turn connects through pipe 76 with the common header pipe 77 which delivers into the slop tank 78.

And each of the main condensing worms 71 connects by pipe 79 with a receiving drum 80 carrying at its top a pressure gage 81. From the bottom of the drum 80 leads a pipe 82 to the meter 83 which is connected by pipe 84 with the pressure-reducing distillate-delivering trap 85 which delivers through the pipe 86 with the main or header 105 87 which delivers through the valve 88 to the crude distillate storage tank 89.

From near the top of each drum 80 there is afforded communication through pipe 90 controlled by valve 91 with a reducing valve 92, which may be of any suitable type, as for example, a Watson reducing valve of the character hereinbefore described, which in turn communicates through pipe 93 with the gas main or header 94 delivering to the scrubber or absorber 95 which delivers gas through the reducing valve 96 to the gas storage tank 97.

A second gas pipe 98 connects with each drum 80 near its top and communicates through the valve 99 with a second gas main or pipe 100 which also delivers into the gas storage tank 97 or to any gas consumption line or other storage tank.

The operation is as follows:

The oil to be treated is charged into the still S to a level corresponding with the upper end of the pipe 3, the drums D and D¹ and their connecting pipes being simultaneously charged with oil rising through the

lower connecting pipes 6 and 7 into the drum D¹ and thence rising through the pipes 8 into and filling the drum D and its pipes 6 and 7 connecting with the still S.

5 The valves 26, 40 and 50 are closed. Fire is started in the furnace chamber 10 and the charged oil gradually raised in temperature, the valve 21 in the sweat-out line 22 being open so that no substantial pressure is maintained on the charge in the still, and as the charge rises sufficiently in temperature the water entrained with the oil will be vaporized into steam and passes off through the pipe 20, valve 21, sweat-out line 22, through 10 the condenser coil 73 where it is condensed into water, which passes through pipe 74 to and through the look box 75, thence through pipe 76, header 77, to slop tank 78. The look box has a transparent wall through 15 which its interior may be observed from the exterior, and upon the cessation of flow of water therethrough and beginning of a flow of oil, the valves 26 and 40 are opened and the valve 21 closed.

20 25 The firing is continued and the temperature of the oil in the still increases, and simultaneously the pressure within the still increases until such point is reached that the reducing valve 46 allows escape of vapors from pipe 45 to pipe 49, the valves 44 and 48 being open. The vapors of heavy oils which may pass from the still S to the air condenser are therein condensed and returned to the still through the runback connections 37 and 39 through the now open 30 35 valve 40.

40 45 The lighter vapors of the desired products are not condensed in the air condenser and pass through the pipe 49 and through the condensing worm 71, where they are condensed into liquid form and then pass into the drum 80 into which is delivered also through the same line 49 and worm 71 gas which is formed in the still S and which 50 55 is carried through the air condenser and through the reducing valve 46 and through the condensing worm 71 to the drum 80. The crude distillate in the drum 80 passes through the meter 83 and thence through the trap 85, the system between the reducing valve 46 and the trap 85 being preferably at a pressure intermediate still and atmospheric pressures. The trap 85 delivers the crude distillate at lower pressure, substantially atmospheric, through the pipe 86 to the main or header 87, from which it is delivered through valve 88 to the crude distillate storage tank 89.

60 65 Simultaneously the gas delivered to the drum 80 through the line 79 is delivered through pipe 90 and valve 91 to reducing valve 92, which reduces its pressure, as for example, to 25 pounds per square inch, which is sufficient to deliver it through pipe 93 and header 94 to and through the scrub-

ber or absorber 95, which extracts from it any entrained oil vapors which the pressure and cooling in worm 71 did not serve to condense to liquid form, and is delivered through reducing valve 96, which further 70 reduces the pressure to slightly above atmospheric, as for example, three or four inches of water, at which pressure it is delivered into the gas storage tank 97, or otherwise disposed of. 75

It will be understood that the scrubber 95 may be omitted, in which case there may be omitted also the reducing valve 96, and in such event the reducing valve 92 may be so adjusted as to deliver the gas at suitable pressure for delivery into storage tank 97. 80

85 The firing is continued until the oil in the still S has been reduced to a residuum of suitable or desired percentage of the volume of the charge. To determine when this stage is reached the valve 101, Fig. 1, is opened from time to time, and when for the first time vapor is delivered through the same and through the water-cooled coil 102 to the outlet 103, it is known that the charge has been sufficiently reduced and has reached a level corresponding with the upper end of the pipe 104 communicating through valve 101 with coil 102. 90

95 The fire is then withdrawn, the reducing valve 46 is by-passed by closing valves 44 and 48 and opening valve 50, whereupon the gas and vapor contents of the still will pass therefrom through the air condenser, thence through the valve 50 to the line 49, and whatever vapors pass over will be condensed in the coil 71 and delivered as liquid, together with the gas passing over, into the drum 80, the connection between the drum 80 and the reducing valve 92 being closed by valve 91. The valve 99 is now opened and the gas escapes gradually through the pipe 98 into the main 100 and is delivered directly into the storage tank 97, or is delivered to any gas supply line or other storage tank. 100 105 110

115 The reducing distillate, that is, the aforementioned condensed vapors passing over when reducing the pressure on the still at the end of a pressure distillation run, is delivered from the drum 80 through the valve 105 into pipe 106, which by-passes the meter 83 and trap 85, into pipe 86 and through pipe 87 into tank 89, the valve 105 being closed during the normal operation of the still; and when reducing the pressure thereon as described, the valve 108 is closed to prevent reducing distillate flowing from the drum 80 through the meter and trap. 120 125

When the pressure on the still has been entirely released, the residuum is pumped out and disposed of as hereinafter described. To free the still of vapors and gases before entry of a cleaner, steam is ad- 130

mitted as through the pipes 109, 110, 111, 112 (Fig. 1) controlled by valves 113, valve 21 being opened to allow escape through sweat-out line 22.

5 After removal of residuum the still may be entered through the man hole 1 and any deposits therein, as of coke or carbon, are removed. Similarly the drums D and D¹ may be entered through the man holes d and d¹ and similarly cleaned of carbon or coke, and the deposits of carbon or coke within the pipes 8 are also removed by devices similar to boiler tube cleaners.

10 The still is then ready for recharging and 15 operation.

In operation of the battery of stills it is preferred that some are always in operation while one or more are being discharged, cleaned and recharged, whereby the system 20 is continuously producing the desired distillate.

For the purposes of carrying out my process, fuel oil or gas oil of 33 Bé. gravity, or of higher or lower gravity, or any other 25 suitable oil lighter or heavier than gas oil or fuel oil, and with an initial boiling point at atmospheric pressure of from 350 degrees F. to 550 or 600 degrees F. or higher, is charged into the still; or crude petroleum 30 may be charged into the still. Heat is applied to the oil under treatment to raise it to a temperature ranging from 650 degrees F. upwardly at the beginning of the run and increasing to 800 degrees F. and upwardly at the end of the run, with resultant 35 destructive distillation, dissociation or cracking of the oil under treatment into saturated and unsaturated hydrocarbons of lower boiling points and gravities, the resultant 40 pressure upon the oil under treatment ranging from above atmospheric upwardly to 300 pounds per square inch gage, or higher, preventing almost completely fractional distillation of the heavier oil under 45 treatment, which is thereby caused to remain in the still and undergo dissociation or cracking. The lower boiling point products, naphtha or gasoline and burning or kerosene oils, and some small amount of the 50 oil under treatment, constitute the crude distillate.

Where a plurality or battery of stills is operated, it is a feature of my invention to maintain the individual stills independent 55 of each other by recourse to pressure-reducing means in association with each still, whereby intercommunication between the stills is prevented.

The independence of the stills is prefer- 60 ably produced by employment of reducing valves 46 located intermediate the stills and the main condenser worms 71. Or the independence of the stills may be procured when the reducing valves 46 are omitted by 65 employing as before the traps 85 and the

reducing valves 92, in which case they will respectively deliver condensate and gas from substantially still pressure to any lower pressure, as atmospheric,

When the reducing valves 46 are not em- 70 ployed, and the devices 85 and reducing valves 92 are employed, the still pressures will exist in the worm 71 and receiver drums 80 down to the devices 85 and valves 92, which reduce the pressure from still pres- 75 sure to any suitable lower pressure. And when the reducing valves 46 are employed and the pressure-reducing devices 85, 92 and 96 are not employed, the pressure in the worms 71 and drums 80 and pipe 87 may

be atmospheric or substantially atmospheric. And where both reducing valves 46 and devices 85 and 96 are employed, as before described, the pressures in the worm 71 and receivers 80 will be intermediate still and

atmospheric pressures. In all these cases, 80 however, the stills are maintained independent of each other in that there is no communication between them. From this struc-

ture and mode of operation there results the 85 advantage that each still is individually controllable and each may be controlled to produce a maximum yield of the desired distillate, with the result that the entire bat-

ttery of stills yields a greater amount of 90 desired distillate than in the case where the stills of the battery are in communication with each other, and therefore all under the same pressure. Where the stills are main-

tained independent, each may be fired at 95 such rate, and under such pressure and temperature conditions that the rate of production of desired distillate is controllable and may be made such as to procure maxi-

mum yield of the desired distillate, with the 100 result, as stated, that the yield of the entire battery of stills may so be made a maximum and greater than in the case where the stills of a battery are in communication with each

other and therefore all operated at the same 105 pressure.

Furthermore, where a battery of stills is 110 operated, some are always in operation, generally at different stages of their runs, while some are being re-charged; and where

there is variation in nature or composition 115 of the charging material from time to time, it follows that different stills of a battery may be operated upon charges differing more or less from each other and therefore

requiring more or less difference in operating conditions as of temperature and pressure and rate of distillation. The independ-

ence of the stills under such conditions accordingly has the further advantage that notwithstanding these differences in the charging materials operated upon, or the difference of the charges due to their hav-

ing arrived at different stages of their re- 120 spective runs, each still may be so operated

as to produce the desired distillate and the desired yield of such distillate, with the result that the yield of the entire battery may be made more uniform as to character and, 5 as previously stated, greater in quantity, than in the case where the stills of a battery are in communication with each other.

By employing reducing valve 46 between the still and the condensing worm 71, as 10 preferred, it is possible to obtain a regulation of still operation more uniform than when the regulating device is located at the outlet of the main condenser, because then still operation is based on changes of conditions at the entrance to the condenser much in advance in point of time of changes that take place at the condenser outlet, and accordingly each still is controllable with greater nicety.

15 The intermediate pressure, that existing between the reducing valve 46 and the trap 85 and reducing valve 92, may be made anything desired, but is ordinarily 40 pounds gage pressure, though it will be understood that it may be suitably higher, as only slightly less than still pressure, for the purpose of preventing large amounts of the light distillate vapors passing off in the gas.

20 The crude and reducing distillates received in the storage tank 89 are operated upon as follows, as will be understood from Fig. 7, constituting a chart illustrative of one of the modes of carrying out my process, it being understood that my invention is 25 not limited thereto.

The crude distillate is charged into fire still No. 1 operated at substantially atmospheric pressure, from which there distils over gasoline distillate. The residuum in the 30 fire still No. 1 is delivered into fire still No. 2, which is also operated at substantially atmospheric pressure and from which there passes overhead a distillate comprising gasoline and a small amount of kerosene or burning oil. The overhead distillates from fire stills Nos. 1 and 2 are mixed and then subjected to treatment by concentrated sulfuric acid, the treated distillate being then charged into a steam still in which the 35 contents are heated, at atmospheric pressure, by a steam coil submerged in the still charge. The distillate passing overhead from the steam still comprises motor gasoline. The residuum in this steam still is kerosene or burning oil, which is then treated with concentrated sulfuric acid with kerosene or lamp oil as the finished product. If, however, the color of the 40 residuum in this steam still is unsatisfactory, it may be charged back into the fire stills above mentioned with the crude distillate from the pressure still.

From fire still No. 2 the residuum is delivered into fire still No. 3, where it is distilled at substantially atmospheric pressure,

the distillate passing overhead therefrom comprising lamp oil or kerosene distillate containing some gasoline or naphtha. The residuum of fire still No. 3 is delivered into fire still No. 4, where at substantially atmospheric pressure there passes overhead a distillate comprising kerosene or lamp oil and some naphtha or gasoline.

70 The residuum in fire still No. 4 is gas oil, which may be delivered to gas oil storage or otherwise disposed of.

These overhead distillates from fire stills Nos. 3 and 4 are mixed and charged into a steam still, from which there passes overhead distillate of gasoline and kerosene, 80 which is acid treated and then further subjected to steam distillation, giving a finished gasoline or naphtha, the residua from these two last named steam stills being mixed and then acid treated to produce a finished lamp oil.

85 The tar or residuum, exclusive of the carbon left in the tubes, drums and still, remaining after a run, comprises oil in the nature of gas oil with carbon or heavy carbonaceous material in suspension therein. This may be charged into a batch fire still and run to dryness, leaving a residuum of coke, the overhead distillate being gas oil which is delivered to gas oil storage or otherwise disposed of.

90 Or in lieu of treating the pressure still residuum in a batch fire still as described, it may be treated with concentrated sulfuric acid to remove the coke-forming materials 100 therein by forming an acid sludge, and the clarified oil may then be retreated according to the hereinbefore described pressure still process, or may be otherwise disposed of.

95 The oil resulting from either the acid treatment or fire distillation of the pressure still residuum contains in solution paraffin wax which is not completely removed in the usual refinery processes and which has not been completely dissociated or cracked into light oil distillates in the pressure still, it being well known in the oil refining art that such paraffin wax readily cracks or dissociates even at atmospheric pressure into 110 naphtha, gasoline and kerosene. Such paraffin wax as remains in the gas oil after the aforementioned acid treatment or fire still treatment of the pressure still residuum may then be recovered by the usual cold pressure or cold settling processes, or otherwise extracted, with or without previous separation of its lighter components. When cold settling, previous removal of lighter components by fractional distillation is preferred. 115 When such fractional distillation is carried on to suitable degree the residuum has valuable lubricating oil properties. And after removal of wax by the aforementioned cold pressing process, the oil may be fraction- 120

125

ally distilled to leave a residuum which has valuable lubricating oil properties.

While the foregoing description relates to the treatment of crude petroleum, petroleum 5 distillate or petroleum residuum, it will be understood that the process and apparatus are applicable also to the treatment of shale oil, coal distillates, and the like. And for brevity in the appended claims the terms 10 "petroleum", "petroleum distillate" and "petroleum residuum" will be understood to include all the aforementioned oils.

What I claim is:

1. The method of producing lighter oil 15 from heavier petroleum, which consists in subjecting the latter to cracking temperature under pressure exceeding atmospheric pressure, stepping down the pressure of the resultant vapors to a substantially lower

20 pressure intermediate said pressure and atmospheric pressure, condensing said vapors into liquid form while under said intermediate pressure.

2. The method of producing lighter oil 25 from heavier petroleum, which consists in subjecting the latter to cracking temperature under pressure exceeding atmospheric pressure, stepping down the pressure of the resultant gas and vapors to a substantially 30 lower pressure intermediate said pressure and atmospheric pressure, cooling said gas and vapors while under said intermediate pressure, separating said gas from the resulting condensate while under said intermediate pressure, and thereafter separately 35 and independently reducing the pressure on said gas and said condensate.

3. The method of producing lighter oil 40 from heavier petroleum, which consists in subjecting the latter to cracking temperature under pressure exceeding atmospheric pressure, stepping down the pressure of the resultant gas and vapors to a substantially 45 lower pressure intermediate said pressure and atmospheric pressure, separating said gas from the resulting condensate while under said intermediate pressure, further reducing the pressure of said gas to a pressure substantially above atmospheric, and scrubbing said gas while under said 50 last named pressure.

4. The method of producing lighter oil 55 from heavier petroleum, which consists in subjecting the latter to cracking temperature under pressure exceeding atmospheric pressure, reducing the pressure of the resultant gas and vapors to a pressure intermediate said pressure and atmospheric pressure, cooling said gas and vapors while under said 60 intermediate pressure, said intermediate pressure being of a magnitude to cause substantial stripping of said gas of oil vapors, separating said gas from the condensate while under intermediate pressure, and 65 thereafter scrubbing the gas.

5. The method of producing lighter oil 70 from heavier petroleum, which consists in subjecting the latter to cracking temperature under pressure exceeding atmospheric pressure, reducing the pressure of the resultant gas and vapors to a pressure intermediate said pressure and atmospheric pressure, cooling said gas and vapors while under said intermediate pressure, said intermediate pressure being of a magnitude to 75 cause substantial stripping of said gas of oil vapors, separating said gas from the condensate while under intermediate pressure, further reducing the pressure of said gas to a pressure substantially above atmospheric and scrubbing the same, and thereafter further reducing the pressure of said gas.

6. The method of producing lighter oil 80 from heavier petroleum, which consists in subjecting the latter to cracking temperature under pressure exceeding atmospheric pressure, removing from the residuum unsaturated hydrocarbons, and thereafter again subjecting said residuum to dissociating or cracking temperature under pressure, 85 whereby lighter oil is produced.

7. The method of producing lighter oil 90 from heavier petroleum containing wax, which consists in subjecting said petroleum and the contained wax to cracking temperature under pressure greater than atmospheric, whereby the heavier oil and wax are dissociated into lighter hydrocarbons, removing from the resultant residuum tarry 95 matter, and thereafter subjecting the clarified residuum to a cracking temperature under pressure in excess of atmospheric pressure.

8. The method of producing wax and 100 lighter oil from heavier petroleum containing wax, which consists in subjecting said petroleum and the contained wax to cracking temperature under pressure greater than atmospheric, whereby the heavier oil and 110 wax are dissociated into lighter hydrocarbons, treating the resultant residuum to remove therefrom color imparting reaction products, and thereafter extracting wax remaining in the clarified solution.

9. The method of producing wax and 115 lighter oil from heavier petroleum containing wax, which consists in subjecting said petroleum and the contained wax to cracking temperature under pressure greater than 120 atmospheric, whereby the heavier oil and wax are dissociated into lighter hydrocarbons, acid treating the resultant residuum, and thereafter removing from said acid treated residuum wax remaining in solution therein.

10. The method of producing wax and 125 oil from petroleum containing wax, which consists in subjecting said petroleum and the contained wax to cracking temperature 130

- under pressure greater than atmospheric, whereby the heavier oil and wax are dissociated into lighter hydrocarbons, acid treating the resultant residuum, thereafter removing from said acid treated residuum wax remaining in solution therein, and reducing said residuum after removal of wax by fractional distillation, leaving a residuum having lubricating oil properties.
11. The method of producing lighter oil from heavier petroleum, which consists in subjecting the latter to cracking temperature under pressure exceeding atmospheric pressure, preliminarily cooling the resultant vapors to cause condensation of heavy vapors without condensation of the vapors of the lighter desired products and returning the heavy condensate to the petroleum under treatment, thereafter stepping down the pressure of the remaining vapors to a substantially lower super-atmospheric pressure and while so under reduced pressure condensing them, separating gas under said reduced pressure, and thereafter separately further reducing the pressure of said gas.
12. The method of producing lighter oil from heavier petroleum, which consists in subjecting the latter to cracking temperature under pressure exceeding atmospheric pressure, preliminarily cooling the resultant vapors to cause condensation of heavy vapors without condensation of the vapors of the lighter desired products and returning the heavy condensate to the petroleum under treatment, thereafter stepping down the pressure of the remaining vapors to a substantially lower pressure intermediate said pressure and atmospheric pressure, and while under said intermediate pressure condensing them.
13. The method of producing lighter oil from heavier petroleum, which consists in subjecting the latter to cracking temperature under pressure exceeding atmospheric pressure, preliminarily cooling the resultant vapors to cause condensation of heavy vapors without condensation of the vapors of the lighter desired products, returning the preliminary condensate to the still, thereafter stepping down the pressure of the vapors of the lighter desired products to substantially lower pressure and while under such reduced pressure condensing them, and separating gas and scrubbing the same while under pressure above atmospheric pressure.
14. The method of producing lighter oil from heavier petroleum, which consists in subjecting the latter to cracking temperature under pressure exceeding atmospheric pressure, preliminarily cooling the resultant vapors to cause condensation of heavy vapors without condensation of the vapors of the lighter desired products, returning the preliminary condensate to the still, thereafter stepping down the pressure of the va-

pors of the lighter desired products to a substantially lower pressure intermediate still and atmospheric pressures, condensing said vapors while under said intermediate pressure, and separating gas while under 70 said intermediate pressure.

15. The method of treating petroleum, which consists in subjecting the same to cracking temperature under pressure exceeding atmospheric pressure, stepping 75 down the pressure of the resultant gas and vapors to a pressure substantially lower than still pressure and substantially above atmospheric pressure, cooling said gas and vapors while under said last named pressure, and upon completion of a run gradually reducing the pressure upon the charge to substantially atmospheric pressure by releasing the vapors of the dissociation products and of the oil under treatment, and 80 condensing said vapors to form a reducing distillate.

16. The method of treating petroleum, which consists in subjecting the same to cracking temperature under pressure exceeding atmospheric pressure, stepping down the pressure of the resultant gas and vapors to a pressure substantially lower than still pressure and substantially above atmospheric pressure, cooling said gas and vapors 95 while under said last named pressure, and upon completion of a run gradually reducing the pressure upon the charge to substantially atmospheric pressure by releasing the vapors of the dissociation products and of 100 the oil under treatment, condensing said vapors to form a reducing distillate, and thereafter fractionally distilling said reducing distillate.

17. The method of producing lighter oil 105 from heavier petroleum, which consists in simultaneously and continuously subjecting a plurality of charges of the latter of substantially similar compositions independently of each other to cracking temperatures 110 under pressures exceeding atmospheric pressure, condensing the resultant vapors at independently maintained pressures substantially above atmospheric pressure, and commingling the condensates to constitute a 115 composite crude distillate.

18. The method of producing lighter oil from heavier petroleum, which consists in simultaneously subjecting a plurality of charges of the latter of substantially similar compositions at different stages of treatment independently of each other to cracking temperatures under pressures exceeding atmospheric pressure, independently condensing the resultant vapors, and commingling the condensates to constitute a composite crude distillate.

19. The method of producing lighter oil 120 from heavier petroleum, which consists in simultaneously subjecting a plurality of 125

130

charges of the latter of substantially similar compositions independently of each other to cracking temperatures under pressures exceeding atmospheric pressure, independently 5 condensing the vapors resultant from said charges at pressures substantially below still and substantially above atmospheric pressures, releasing the condensates and commingling them to constitute a composite 10 crude distillate.

20. Petroleum treating apparatus comprising a pressure still, a fire chamber external thereto for heating the oil therein to cracking temperature, a preliminary condenser, a vapor connection between said still and said preliminary condenser, a main condenser, an automatic pressure reducing valve between said condensers for delivering to said main condenser oil vapors at a super-atmospheric pressure substantially below the pressure in said preliminary condenser, and means for maintaining said super-atmospheric pressure in said main condenser. 20

21. Petroleum treating apparatus comprising a pressure still, a condenser in which vapors are condensed under pressure, an automatic trap delivering the condensate to lower pressure and preventing escape of gas, and automatic means for separately reducing the pressure of the gas. 25

22. Petroleum treating apparatus comprising a pressure still, a preliminary condenser, a vapor connection between said still and preliminary condenser, a main condenser, an automatic pressure reducing valve delivering oil vapors to said main condenser at a super-atmospheric pressure substantially below the pressure in said preliminary condenser, and condensate-delivering pressure reducing means maintaining said super-atmospheric pressure in said main condenser and delivering condensate therefrom at lower pressure. 35

23. Petroleum treating apparatus comprising a pressure still, a preliminary condenser, a vapor connection between said still and said condenser, a main condenser, a pressure reducing valve between said condensers for maintaining in said main condenser a 50 pressure substantially below the pressure in said preliminary condenser and substantially above atmospheric pressure, a receiver receiving gas and condensate from said main condenser, a gas connection leading from said receiver, and a pressure reducing valve in said gas connection. 55

24. Petroleum treating apparatus comprising a pressure still, a preliminary condenser, a vapor connection between said still and said condenser, a main condenser, a pressure reducing valve between said condensers for maintaining in said main condenser a pressure substantially below the pressure in said preliminary condenser and substantially above atmospheric pressure, a 60

70 receiver receiving gas and condensate from said main condenser, a gas connection leading from said receiver, a pressure reducing valve in said connection, a scrubber to which gas is delivered through said connection, and a reducing valve through which gas is delivered from said scrubber.

25. Petroleum treating apparatus comprising a pressure still, a preliminary condenser, a vapor connection between said still and said condenser, a main condenser, a pressure reducing valve between said condensers for maintaining in said main condenser a pressure substantially below the pressure of said preliminary condenser and substantially above atmospheric pressure, a receiver receiving gas and condensate from said main condenser, pressure-reducing condensate-delivering means through which condensate from said receiver is discharged at low pressure, a gas connection with said receiver, and a pressure reducing valve in said connection. 75

26. Petroleum treating apparatus comprising a pressure still, a preliminary condenser, a vapor connection between said still and said condenser, a main condenser, a reducing valve between said condensers, and a valve for by-passing said reducing valve. 80

27. Petroleum treating apparatus comprising a pressure still, a fire chamber for heating the oil therein to cracking temperature, a preliminary condenser, a vapor connection between said still and said condenser, a main condenser, a pressure reducing valve between said condensers for maintaining in said main condenser a pressure substantially below the pressure of said preliminary condenser and substantially above atmospheric pressure, a runback from said preliminary condenser to said still, and means delivering condensate from said main condenser to a region at a pressure lower than existing in said main condenser. 95

28. Petroleum treating apparatus comprising a pressure still, a preliminary condenser comprising initial and terminal headers, a plurality of tubes connecting said headers, runback connections from said headers to said still, a main condenser, and a pressure reducing valve between a terminal header of said preliminary condenser and said main condenser for maintaining in said main condenser a pressure substantially below the pressure in said preliminary condenser and substantially above atmospheric pressure. 100

29. Petroleum treating apparatus comprising a battery of pressure stills, a condenser for each still in which vapors from said still are condensed under pressure, each still and condenser being independent of the other stills and condensers, a pressure-reducing connection between each still and its condenser for effecting in said condenser a pres- 105

sure substantially below said pressure and substantially above atmospheric pressure, a pipe receiving condensate from all said condensers, and a pressure-reducing connection 5 between each of said condensers and said pipe.

30. Petroleum treating apparatus comprising a battery of pressure stills, a condenser associated with each still, each still

and condenser being independent of the 10 other stills and condensers, distillate receiving means, and fluid-delivering pressure-reducing means between each of said condensers and said receiving means.

In testimony whereof I have hereunto 15 affixed my signature this 27 day of March, 1917.

JOSEPH W. LEWIS.
